LLANERCH, PENNSYLVANIA

MOTION TOY

Application filed May 29, 1928. Serial No. 281,446.

This invention relates to improvements in toys and more particularly to motion toys or in other words those which are operable to simulate motion, and the general object of the invention is to provide a toy embodying a figure representing a dancer and which figure has jointed limbs, in combination with a vibratory platform through the vibration of which the limbs may be caused to move thus adapting the figure to simulate the movements of a dancer, and, in this connection, the invention contemplates a novel arrangement of the platform in such manner that it may be manually vibrated with little effort.

Another object of the invention is to provide a motion toy of the class described embodying the combination of a figure having articulated limb members, a platform, means supporting the platform for oscillatory movement, and resilient means for yieldably resisting tilting movement of the platform, so that by a quick manual downward thrust upon either end of the platform and a release of pressure, the resilient means will, in returning the platform to normal position, cause a vibration thereof, bringing its surface into and out of contact, repeatedly, with the feet portion of the limb members of the figure so as to cause the limb members to move in a manner simulating the movements of a dancer.

Another object of the invention is to provide a motion toy of the class described which will be devoid of mechanical operating parts for imparting motion to the figure of the toy, such for example as spring or other motors, gears, or the like, and which toy will be exceptionally simple in its construction and capable of having any of its component parts readily replaced at an exceptionally low cost.

As previously stated, the invention contemplates the provision, in connection with the figure and its articulated limb members, of a vibratory platform, and another object of the invention is to employ, as the yieldable or resilient movement resisting means referred to above, for association with the platform, resilient parts, such as ordinary rubber bands, which may be readily obtained upon

the market and replaced whenever they become worn or deteriorated or break, so that the employment of expensive springs is entirely obviated and, due to the nature of these elements they may be readily replaced.

While the accompanying drawings and the description which is to follow, constitute a disclosure of the preferred embodiment of the invention, it will be understood that various changes may be made within the scope of what is claimed.

In the accompanying drawings:

Figure 1 is a view in side elevation of the toy embodying the invention;

Figure 2 is a front elevation of the toy;

Figure 3 is a horizontal sectional view taken substantially on the line 3—3 of Figure 1 looking in the direction indicated by the arrows.

The toy, embodying the invention, may be made from any inexpensive material such for example as wood, and the same comprises a base 1 which may be of oblong rectangular form or any other desired marginal contour, and secured at opposite points to the base are the lower ends of a pair of uprights 2 which extend parallel to each other and, in this instance, substantially midway between the ends of the base. These uprights are connected at their upper ends by a cross piece which is indicated by the numeral 3 and, for a purpose which will now be described, spaced arms 4 project, in the illustrated embodiment of the invention, from one side of said cross piece in parallel relation to each other.

The figure of the toy is indicated in general by the numeral 5 and may represent a clown or any other dancing performer, and this figure may likewise be made of wood and includes, in its structure, a body 6 which is formed at the portions thereof which represent the shoulders of the imitated performer, with a transversely extending bore indicated by the numeral 7, a pin 8 being fitted through this bore and mounted at its ends in the ends of the supporting arms 4, the body of the figure being in this manner suspended for free swinging movement between the said arms 4 and, while the support-

ing arms 4 may likewise represent the arms of the imitated performer, it is preferable that the figure embody arm members 9 which are likewise suspended from the pin 8 between the body 6 of the figure and the ends of the said arms 4, the arms 9 being preferably formed in a plurality of sections 10 pivotally connected as indicated by the numeral 11 so as to represent the upper and fore arm of the imitated performer.

The figure 5 further embodies limb members which are indicated in general by the numeral 12 and which may be also formed of wood, and each of these members preferably comprises upper and lower sections 13 and 14 respectively pivotally connected by a pivot joint 15 such as illustrated in the drawings and consisting for example of interfitting ears upon the meeting ends of the two sections, and a pivot pin fitted through the said ears. The leg members 12 have their upper sections 13 pivotally suspended from the lower end of the body 6 of the toy by providing ears 16 at the upper ends of the sections 13 and arranging these ears in notches 17 formed in the said lower end of the body 6, a pivot pin 18 being fitted transversely through the body and extending across the notches and through openings in the said ears 16. It is also preferable that each limb member 12 be so constructed as to include, in addition to the upper and lower sections 14, foot sections 19 pivotally connected at their upper ends as at 20 to the lower ends of the limb sections 14. Preferably all of the pivotal connections between the component parts of the figure 5 of the toy will be sufficiently loose to permit of free relative movement of the connected parts, so that, in the operation of the toy, as will presently be described, the component parts of the limb members and the arm members may have independent movement about connecting pivots and the body of the figure 45 may likewise have free pivotal movement upon the supporting pin 8.

The means provided for imparting a jiggling motion to the figure 5 so that its component body, limb, and arm members may have movement simulating the movements of corresponding portions of the body of a dancer, includes a platform 21 which is preferably of approximately the same marginal contour as the base 1, although it may have some other contour, and this platform is pivotally supported midway between its ends and between the uprights 2 by small trunnions or pivot pins 22 which are secured through the uprights at points spaced above the base 1 and fit loosely in sockets in the lateral edges of the platform. As stated above, the pins 22 which tiltably support the platform 21, are located above the plane of the base 1 of the toy and consequently the

platform 21 is supported in spaced relation to the upper side of the base and it will be observed by reference to Figures 1 and 2 that when the platform 21 is in true horizontal position, the foot members 19 of the figure 5 will rest upon the platform. In order that vibratory motion or quick oscillation of the platform 21 may be effected in order to impart motion to the limb, arm and body members of the figure 5, pins 23 and 24 are secured in the end edges of the base 1 and platform 21, and rubber bands 25 are engaged about the pins at each end of the structure.

The rubber bands 25 referred to above will be of equal size and therefore the platform 21 will be yieldably held in a true horizontal position. In the illustrated embodiment of the invention the figure is located at one side of the uprights 2 and it will now be evident that if the platform, at the other side of the uprights, is given sudden and intermittent taps with the fingers of the one using the toy, and the force and extent of these taps is varied from time to time, the platform 21 will be vibrated or caused to oscillate irregularly about its pivots 22 and as a result its portion which is below the figure 5 will strike the foot members 19 of the figure and, due to the free pivotal suspension of the limb members of the figure and the free suspension of the body of the figure and the arm members thereof, and likewise due to the irregular and intermittent oscillation of the platform, will be caused to go through many amusing changes in position which are so varied in their character that the toy will prove much more interesting and amusing than are toys which are purely mechanically operated and the moving parts of which are actuated in a predetermined sequence and manner. It will be understood that in tapping the platform, as the finger of the user is lifted from the platform, the rubber bands 25 will, through their resiliency, tend to restore the platform to a horizontal position, and therefore the rubber bands serve substantially with the same effectiveness in imparting irregular oscillation to the platform as do the fingers of the user of the toy. Another advantage of the structure shown and described is that by tapping the platform 21 at successive periods and, after each tap, permitting the rubber bands to restore the platform to its true horizontal position, the figure may be caused to successively assume various different attitudes representing postures which might be assumed by a performer.

Having thus described the invention, what I claim is:

1. As an article of manufacture, a toy including a base, parallel uprights fixed to and extending upwardly from said base, a figure, means carried by said uprights and supporting said figure, an elongated platform extend-

ing between said uprights, means pivotally supporting said platform upon said uprights below said figure and above said base, a pin carried by each end of said platform and said base, and elastic bands yieldably connecting the pins of the platform to the pins of the base, as and for the purposes set forth.

2. As an article of manufacture, a toy including a base, parallel uprights fixed to and extending upwardly from said base, a figure, means carried by said uprights and supporting said figure, an elongated platform extending between said uprights, means pivotally supporting said platform upon said uprights below said figure and above said base, and yieldable means connecting each end portion of said platform to a corresponding portion of said base, as and for the purposes set forth.

20 In testimony whereof I affix my signature.
CHARLES R. CREW.
